UNITED STATES PATENT OFFICE.

JULIUS H. RAST, OF CHARLESTON, SOUTH CAROLINA.

SADDLE-POST AND PUMP FOR BICYCLES.

SPECIFICATION forming part of Letters Patent No. 668,214, dated February 19, 1901.

Application filed August 2, 1899. Serial No. 725,913. (No model.)

To all whom it may concern:

Be it known that I, JULIUS H. RAST, of the city of New York, State of New York, at present residing at Charleston, in the county of 5 Charleston and State of South Carolina, have invented certain new and useful Improvements in Saddle-Posts and Pumps for Bicycles, of which the following is a specification.

The principal object of this invention is to 10 provide a powerful, inexpensive, and durable pump for inflating the pneumatic tires of bicycles or other vehicles and so arranged that the tubular saddle-post stem also forms the pump-cylinder. This cylinder may be 15 utilized to hold various implements or appliances of a repair-kit, if the rider so desires.

The invention also includes a novel clamping device adjustable on the saddle-post stem and adapted to engage the vehicle-frame and 20 providing for vertical adjustment of the saddle and for holding it safely at any desired height.

The invention will first be described and then will be particularly defined in claims 25 hereinafter set forth.

Reference is made to the accompanying drawings, forming part of this specification, and in which similar numerals indicate corresponding parts in the different views.

Figure 1 is a sectional side elevation of the saddle-post and pump as adjusted to a fragmentary portion of a bicycle-frame and with the preferred air-discharge tube projecting from the post-head and with a repair-kit in 35 the pump-cylinder. Fig. 2 is a detail sectional view showing the air-tube housed and locked within the saddle-post head and also showing how a bushing may be used to adapt the same saddle-post and pump to another frame- 40 tube of larger diameter. Fig. 3 illustrates at a much smaller scale the preferred manner of using the pump. Fig. 4 is a vertical section, and Fig. 5 is a top plan view, of the saddle-post clamp-nut. Figs. 6 and 7 are re- 45 spectively a side elevation and bottom plan view of the clamping-collar which is fastened to the saddle-post stem by the clamp-nut; and Fig. 8 is a detail broken sectional elevation of the means employed for holding up 50 the pump-piston and retaining the repair-kit when the saddle-post is normally adjusted to the bicycle-frame.

In Figs. 1 and 3 of the drawings the numeral 1 indicates the perch-tube of a bicycle-frame, into which passes the tubular stem 2 55 of the saddle-post. The tubular head 3 of this post is adapted to support the saddle 4 in any approved manner. The parts 2 3 communicate internally by a suitable opening 5 in the head. The head is closed at its 60 front end 6, thus forming behind the air-current from opening 5 to the wheel-tire an air reservoir or chamber 7. At its other end the head 3 is adapted to discharge air. I prefer to provide for air-discharge by forming on 65 the head 3 a suitable screw-thread 8, (preferably an internal thread,) to which the opposite threaded ends 9 10 of the coupling 11 of the air-tube 12 are adapted. When thread 9 engages thread 8, the tube 12 is adjusted 70 for use outside the head, as shown in Figs. 1 and 4, and when thread 10 engages thread 8 the air-tube is housed and locked invisibly within the seat-post head 3, as shown in Fig. 2 of the drawings. This head 3 is suffi- 75 ciently thick to prevent indentation of it by the saddle-fastening bolt. Hence there will be no obstruction within the head to the entrance and exit of the air-tube 12. This tube has any suitable nipple 13 adapted to the 80 valve of the wheel-tire 14.

The saddle-post stem 2 serves as the pump-cylinder in which is fitted any approved form of piston 15, which is fastened to a rod 16, adapted to move freely through an aperture 85 17 in a removable plug 18, which is screwed to the lower end of stem 2 to close it. I preferably use an external thread on the plug engaging an internal thread of the stem. The plug 18 is counterbored and internally threaded to receive the coarse external thread 19 on a locking-nut 20, which has an axial internal thread of finer pitch engaging a corresponding fine thread 21 on the piston-rod 16, as more clearly shown in Fig. 8 of the drawings. When 95 the nut 20 is unscrewed from plug 18, the rod 16 is freed to permit reciprocation of the piston 15 in the seat-post stem or cylinder 2 for working the pump, the nut 20 meanwhile moving with the rod. The moving rod is guided by 100 the plug-aperture 17, which also supplies the pump-cylinder with air which passes in front of the yielding piston 15 on its back stroke in the usual manner. After use of the pump

the piston is pushed fully forward or inward, and the nut 20 is screwed by its thread 19 into the plug 18 until the difference in the pitch of the two threads 19 21 causes a binding of the piston-rod to hold the rod and piston firmly up to normal position, as shown in Fig. 1 of the drawings, and preventing noisy loose jarring or shaking of them in the bicycle-frame, no matter how rough the road may be over which the bicycle travels.

Suitable wrenches 22 23, tape 24, tire-puncture fluid 25, and fluid-applying needle 26, or other articles usually in a repair-kit, may be placed within the cylinder 2, thus dispensing with the ordinary tool-bag at the will of the rider. The repair-kit is accessible by unscrewing the plug 18 from the stem 2. The kit is of course removed and the plug 18 is replaced when the pump is to be operated.

20 In using the pump I prefer to lift the stem 2 from the perch-tube 1 and leave the saddle 4 on the head 3 and then invert parts 2 3 4 and couple the tube 12 to the tire 14 while the saddle rests on the ground and then work 25 the pump by reciprocating the piston by means of its rod-handle 27 and as will be understood from Fig. 3 of the drawings. The reserve air-chamber 7 behind aperture 5 promotes steady and effective forcing of the air 30 through tube 12 into the tire. When the tire is fully inflated, the tube 12 is disconnected from it and will then be reversely connected with the seat-post head 3, as shown in Fig. 2 of the drawings, and thus will be fully protected within said head from the weather 35 when the post and saddle are readjusted to the bicycle-frame, as indicated by dotted lines in Fig. 3 of the drawings.

Besides providing for use of the saddle- 40 post as a pump-cylinder I also provide an improved means for supporting the post in the bicycle-frame, which permits any desired vertical adjustment of the saddle, while preventing its lateral twisting or turning in the frame.

45 This saddle-supporting means also permits quick and convenient removal and replacement of the post when the pump is to be used and without changing the height adjustment of the saddle. I accomplish these ends by 50 means of a clamp-collar device adapted to be fastened at any point to and around the saddle-post stem and having a tongue-and-groove connection with the frame. The clamp-collar device is clearly distinguished from the

55 ordinary bicycle seat-post or handle-bar fastening in that said clamp-collar when once adjusted on the seat-post stem to give proper height of the saddle always remains fixed to the stem and is bodily lifted with the stem

60 from the frame. Hence there are no nuts or other parts to loosen before the pump can be removed from the frame, and no tightening of nuts is necessary when the seat-post is readjusted to the frame for riding purposes 65 after use of the pump. Removal and replacement of the pump relatively to the frame are thus quickly and most conveniently ef-

fected with the assurance that the saddle height is unchanged after readjustment of the stem in the frame. This clamp-collar or 70 device may have various forms to serve these purposes. I prefer to make it with an inner split sleeve 28, which has a tongue 29, the opposite edges of which fit a groove 30 in the frame perch-tube 1. The vertical side slit or 75 slot 31 of the sleeve permits it to be tightly clamped to the saddle-post stem 2 by a nut 32, which has a downwardly-flaring internal screw-thread 33, engaging an upwardly-tapering external thread 34 on the sleeve. As a 80 further improvement I bevel the face of the tongue 29 at 35 and make the groove 30 with a corresponding inclined wall or a suitable contact-point, so that when the saddle is adjusted to the frame the tongue and groove 85 will not only prevent lateral turning of the saddle, but will also wedge the saddle-post over firmly against the opposite side wall of the perch-tube, and thereby prevent the post and its saddle from working loose or jumping 90 dangerously in the vehicle-frame. The tongue 29 may be on the frame and the groove 30 in the clamping device; but I prefer the construction herein shown and described.

Fig. 2 of the drawings shows how the same 95 saddle-post and pump may be adjusted to a bicycle-frame having a larger perch-tube 1^a by tightly driving a bushing 36 into said tube and providing this bushing, which loosely fits the post-stem 2, with a groove 30, receiving 100 the tongue 29 of the clamping device. The same saddle-post and saddle, with the pump and all other appliances, thus may be used with bicycles of different style or construction by the same rider or by different riders. 105

By permitting very quick and convenient removal of the entire saddle-post and saddle from the bicycle-frame my invention also promotes safety of the vehicle against thieves.

Should a different height of saddle be desired, it is only necessary to loosen the nut 32 and then slide the entire clamping device 28 32 on the saddle-post stem to the desired position and again tighten the nut 32 on the split sleeve 28. Other forms of clamping devices fitting the post-stem and having tongue-and-groove connection with the frame may be vertically adjusted on the stem for regulating the height of the saddle within the scope of my invention. 115

I claim as my invention—

1. A bicycle or vehicle saddle-post adapted to and removable from the vehicle-frame and having a tubular stem serving as a pump-cylinder and having suitable air-outlet, combined with a piston fitted in said stem and having a rod, and a removable plug fitted to the lower end of said stem and having an aperture guiding the reciprocating piston-rod, substantially as described. 125

2. A bicycle or vehicle saddle-post adapted to and removable from the vehicle-frame and having a tubular stem serving as a pump-cylinder and having suitable air-outlet, com-

bined with a piston fitted in said stem and having a rod provided at its handle end with an external screw-thread, a removable plug fitted to the lower end of the saddle - post 5 stem and having an aperture guiding the reciprocating piston-rod and also having an internal screw-thread, and a nut having an external screw-thread fitting the internal thread of the plug and also having an interior thread of different pitch fitting the piston - rod screw - thread, substantially as described.

3. The piston-locking device comprising a plug fitting the pump - cylinder and having an aperture for free passage of the piston-rod and also having an internal screw-thread, said piston - rod having an external screw-thread, and a nut having an external thread fitting said internal screw-thread of the plug 20 and also having an interior thread of different pitch fitting the piston-rod screw-thread, substantially as described.

4. A bicycle or vehicle saddle - post comprising a tubular stem having an air - inlet 25 and forming a pump-cylinder and a connected tubular head adapted to sustain the saddle and communicating by an opening with the stem, said head having at one end or behind said opening a closed reserve air-chamber and 30 adapted at its other end for discharge of air, substantially as described.

5. A bicycle or vehicle saddle - post comprising a tubular stem having an air - inlet and forming a pump-cylinder, and a communicating saddle-sustaining head closed at one 35 end whereat is formed a reserve air-chamber, and having a screw - thread at its discharge end, combined with an air - tube having a coupling provided with two screw - threads 40 each adapted to the post-head thread and providing for holding the air-tube either projected for use or housed within the post - head, substantially as described.

6. The combination, with a bicycle or vehicle frame, of a saddle-post adjustable by its 45 stem in the frame and constituting a pump-cylinder, and a clamping device adjustable on the post-stem for regulating the height of the saddle and having a tongue-and-groove 50 connection with the frame preventing lateral turning of the saddle; said saddle-post being bodily removable from the frame without loosening the clamp thereby providing for independent use of the pump, and for secure 55 replacement of the saddle for riding purposes, substantially as described.

7. The combination, with a bicycle or vehicle frame, of a saddle-post adjustable by its stem in the frame and constituting a pump-

cylinder, and a clamping device adjustable 60 on the post-stem for regulating the height of the saddle and having a tongue-and-groove connection with the frame preventing lateral turning of the saddle, said tongue-and-groove connection also having faces tightly wedging 65 the post-stem laterally in the frame; said saddle - post being bodily removable from the frame without loosening the clamp thereby providing for independent use of the pump, and for secure replacement of the saddle for 70 riding purposes, substantially as described.

8. The combination, with the vertically-adjustable saddle-post stem constituting a pump-cylinder and the notched vehicle-frame, of a split collar having an external tapered 75 screw-thread and also having a tongue adapted to the frame-notch, and a clamp-nut having a tapered internal thread adapted to the collar-thread for tightening the collar on the saddle-post; said saddle-post being bodily removable from the frame without loosening the clamp thereby providing for independent use of the pump, and for secure replacement of the saddle for 80 riding purposes, substantially as described.

9. The combination, with the vertically-adjustable saddle-post stem constituting a pump-cylinder and the notched vehicle-frame, of a split collar 28 having tongue 29 with tapered face 35 adapted to the frame-notch and 90 also having an external tapered thread 34, and a clamp-nut 32 having an internal tapered thread 33 adapted to the collar-thread 34 for holding the saddle-post to the frame; said saddle-post being bodily removable from 95 the frame without loosening the clamp thereby providing for independent use of the pump, and for secure replacement of the saddle for riding purposes, substantially as described.

10. The combination, with the saddle-post 100 bodily removable from the frame and an adjustable clamping device on the post - stem regulating the height of the saddle and having a tongue, of a bushing fitted in the vehicle-frame and adapted to the outside of the 105 saddle-post, said bushing having a recess to which the saddle-post clamp-tongue is adapted, substantially as described, whereby a vertically-adjustable saddle-post adapted to fit directly within a smaller frame-tube may, by 110 means of the bushing, be fitted also to a larger frame-tube and whereby also the axial turning of the saddle-post in the frame is prevented, as set forth.

JULIUS H. RAST.
